UNITED STATES PATENT OFFICE.

DAVID CONLAN, JR., OF BROOKLYN, NEW YORK.

ELECTRICAL APPARATUS.

1,363,394.

Specification of Letters Patent. Patented Dec. 28, 1920.

Application filed January 5, 1920. Serial No. 349,611.

To all whom it may concern:

Be it known that I, DAVID CONLAN, Jr., a citizen of the United States of America, and a resident of Brooklyn, Kings county, and a State of New York, have invented certain new and useful Improvements in Electrical Apparatus, of which the following is a specification.

My present invention relates particularly to apparatus for the distribution of electric current.

The objects of the invention are to improve and to add to the utility and availability of such apparatus particularly as regards the supplying of current to translating devices of the portable type, such as electric heaters, flat irons, vacuum cleaners and the like.

To these ends my invention resides in certain novel features of construction, combinations and arrangements of parts, all of which will be set forth in the following specification which is to be read in conjunction with the drawings accompanying and forming a part hereof and in which I have illustrated the invention embodied in two of its different forms.

In the drawings referred to, Figure 1 is a broken and more or less diagrammatic view illustrating an application of the invention to a switch of the pendant or overhead type and showing a use of the invention for independently carrying current to a portable lamp and to an electric flat iron.

Fig. 2 is an enlarged detail view, partly in section, of the pendant switch and the attachment plug for taking off current therefrom, this view of the switch being taken looking in the direction of the arrow 2 in Fig. 3.

Fig. 3 is a vertical sectional view of the switch and plug in engaged relation, said view being taken on substantially the plane of line 3-3 of Fig. 2.

Fig. 4 is a top plan view of the switch mechanism as removed from the shell or switch casing.

Fig. 5 is a cross sectional view taken on substantially the plane of line 5-5 of Fig. 3.

Fig. 6 is a vertical sectional view as taken on substantially the plane of line 6-6 of Fig. 4.

Fig. 7 is a view of the switch showing both the plugs illustrated in Fig. 1 as en-

gaged therewith and illustrating the first or upper plug as in section.

Fig. 8 is a top plan view of the first or upper plug.

Fig. 9 is a partly sectional view of a modified construction.

Fig. 10 is a top plan view of this form of the switch as removed from its casing.

One of the special features of my invention is the utilization of pendant switches such as are now used to a large extent for controlling overhead or distant lighting circuits, as outlets for supplying current to portable devices which it may be desired to use in the vicinity of the overhead circuits. I have accordingly shown such an adaptation of my invention in Fig. 1, where 15 designates an overhead lighting fixture of more or less common construction supplied with current from the feed wires 16, 17 and 18. This pendant switch is indicated as of the push-button type and is shown as connected in the lamp circuit by means of the cord having incorporated therein a wire 19 connected with the fixture and a wire 20 connected with one of the feed wires. The other side of the fixture is connected by a conductor 21 with the other feed wire and the two cord wires 19 and 20 are connected with binding posts 22, 23 on the switch and in electrical connection with the switch contacts 24, 25. The switch contacts are, in the illustration, arranged to be bridged by an oscillating or movable contact piece 26 which is under control of the push-button 27, from all of which it will be apparent that the pendant switch may be operated to cut the overhead fixture into or out of circuit at will.

In addition to the two wires described, the cord of the pendant switch, in my invention, carries a third wire 28 which is directly connected with the other side of the line and is entirely independent of the overhead circuit described. This gives two wires, designated 20 and 28 in the illustration, which lead direct from the feed wires to the pendant switch structure. This third wire is connected with the third binding post 29 which is independent of and has no connection with the circuit controlling switch contacts.

In the first form of the invention illustrated, all three of these binding posts are

permanently mounted on top of the insulating switch base 30, which base is shown in Fig. 3 as chambered or recessed in its lower end as at 31 to receive and form a 5 housing for the switch contacts.

The switch is provided, in addition to the circuit controlling contacts described, with a pair of outlet contacts or current extension posts 32 and 33 which are mounted on 10 the switch base, but project down below the chambered portion thereof into position to be engaged by the contacts or terminal blades 34, 35 of an attachment plug, such as that shown at 36. The attachment plug designated 36 is illustrated as of the usual or conventional type, having blades projecting from the face thereof and serving as terminals of the cord circuit 37 which, in this instance, is illustrated as led to a current 15 translating device in the form of an electrically heated flat iron 38.

The current extension posts 32 and 33 are shown as made of spring metal and shaped in the form of spring clips so as to be frictionally engaged by the attachment 20 plug blades. One of these posts is shown as electrically connected with the line binding post 22 of the switch, by being engaged beneath the foot portion of the "live" switch 25 contact 24. The other current extension post 33 is shown as connected with the third or extra binding post 29 by having its base portion 39 held by the rivet 40 which is used to secure the binding post 29 on the 30 base. The first terminal post 32 is electrically connected with the first switch contact 24 and so no insulation is required between these parts. The second terminal post 33 is, however, electrically independent 35 of and disconnected from the other switch contact 25 and for this reason I have shown the leg portion 41 of such post as extended up on the outside of the insulating switch base and thence extended in through an 40 opening 42 in the side of said base into the chamber therein at a point removed from the switch contact 25.

The two current extension contacts or terminal posts are preferably housed within 45 a supplementary base portion 43 which may be made as a separate block of insulating material applied to the lower end of the main switch base and resting on an inturned shoulder 44 provided at the lower end of the 50 switch housing or shell 45, said base portion 43 having suitable sockets 46 to receive the extension posts and the attachment plug blades which engage therewith.

From the disclosure thus far it will be seen 55 that the overhead circuit may be controlled in the usual way by means of the pendant switch and that in addition, current may be taken off at this point at any time for supplying various forms of translating devices, 60 such as flat irons, vacuum cleaners and the

like and these entirely independently of the condition of the pendant switch. This means that a vacuum cleaner, for instance, may be connected in circuit by simply "plugging" into the pendant switch and be 70 operated irrespective of whether the overhead circuit controlled by the switch is either "off" or on. This is an important consideration where, for instance, the translating device may draw more current than it would 75 be proper to use in conjunction with the overhead fixture, in which event the switch could be operated to cut out the overhead fixture while using the extension cord circuit. Another of the many conditions where such 80 a combination is of particular value is the case where the overhead fixture is in the form of a light which may or may not be desirable to use in conjunction with the device of the extension cord circuit. 85

In many instances it is desirable to couple a plurality of translating devices in circuit. I have illustrated such a condition in Fig. 1, wherein a small portable light is illustrated at 50 for illuminating at close quarters the 90 work being operated on by the electric iron. This portable lamp is supplied through a cord 51 connected with an attachment plug 52 which is of special novel construction, being provided both with projecting terminal blades 53, 54 for engagement with the extension posts 32, 33 of the pendant switch and with downwardly projected extension posts 55, 56 electrically connected with the terminal blades and seated in sockets 57, 58 100 in the base of plug 52 in position to be engaged by the projecting blades 34, 35 of the other attachment plug 36.

There are thus provided two attachment 105 plugs which are interchangeably engageable with the pendant switch and which may both be used with the switch, as indicated in Fig. 1. This permits, in the illustration, the use of both the portable lamp and the flat iron, or the operation of either one of these singly 110 and also the use of either or both of these devices, with or without using the overhead fixture. The invention thus provides for a great many possibilities and enables the use of various portable devices to meet various 115 different requirements.

In the "compound" attachment plug, 52, the cord wires 51 are preferably brought to the binding posts of the plug through an opening 58^a provided in the side of the plug 120 base so as not to interfere with the second plug.

In order that my invention may be adapted to and employed in conjunction with commercial switches now on the market, I 125 have disclosed the same in Figs. 9 and 10 in the nature of an attachment applicable to switches of the well known "Cutler Hammer" pendant push-button type. Such a switch is illustrated at 60 in the figures re- 130

ferred to. In applying my invention thereto, I provide one terminal post 32^a which is extended up outside the base of the switch, as shown at 61 and is formed at the top with 5 a foot portion 62 which is caught beneath the screw of the binding post 22^a. The other terminal post 33^a is also extended up outside the switch base, as shown at 63 and is turned over the top of the base and there provided 10 with a binding post 29^a which forms the necessary third terminal. As a part of the attachment, I provide the sub-base 43^a resting on the inturned flange 44^a of the shell 45^a and formed with the sockets 46^a designed to 15 house the contact portions of the extension posts and to receive the blades of the attachment plug. The extension posts and sub-base are held in assembled relation by the engagement of said posts in the lateral passages 64 which construction may also be employed for the same purpose in the first 20 form of the device disclosed.

It will be seen that the invention may either be constructed as an entirely new unit 25 or that it may be combined with ordinary commercial switches. It will be apparent also to those skilled in the art that various modifications may be made without departure from the true spirit and scope of the 30 invention as defined in the appended claims.

The portable devices which are supplied by the attachment plugs may have individual control switches, as more or less customary in such devices and they may be controlled either by such individual switches or 35 simply by the connection and disconnection of the attachment plugs.

What I claim is:

1. In electrical apparatus, a pendant 40 switch having means for connecting the same with a feeder circuit and an overhead or remote circuit and switch mechanism for controlling a translating device in the overhead or remote circuit, said pendant switch 45 being provided with insulating sockets in the bottom thereof, terminal posts in said sockets for engagement by the terminal blades of an attachment plug, and means for connecting said terminal posts with the 50 feeder circuit independent of the switch controlled circuit to thereby provide an extension outlet from the feeder circuit uncontrolled by the switch mechanism.

2. In electrical apparatus, a pendant 55 switch having means for connecting the same with a feeder circuit and an overhead or remote circuit and switch mechanism for controlling a translating device in the overhead or remote circuit, said pendant switch 60 being provided with insulating sockets in the bottom thereof, terminal posts in said sockets for engagement by the terminal blades of an attachment plug, and means for connecting said terminal posts with the feeder 65 circuit independent of the switch controlled

circuit to thereby provide an extension outlet from the feeder circuit uncontrolled by the switch mechanism, an attachment plug having a pair of projecting terminal blades on the top thereof to engage the terminal 70 posts in the insulating seats in the bottom of the pendant switch, said attachment plug further having a pair of insulating sockets open to the bottom thereof and terminal posts housed therein and connected with the 75 terminal blades at the top of the attachment plug, and binding posts on said attachment plug electrically connected with the terminal blades, for the connection of an extension circuit. 80

3. In electrical apparatus, a pendant switch having means for connecting the same with a feeder circuit and an overhead or remote circuit and switch mechanism for controlling a translating device in the 85 overhead or remote circuit, said pendant switch being provided with insulating sockets in the bottom thereof, terminal posts in said sockets for engagement by the terminal blades of an attachment plug, and 90 means for connecting said terminal posts with the feeder circuit independent of the switch controlled circuit to thereby provide an extension outlet from the feeder circuit uncontrolled by the switch mechanism, the 95 means for connecting the pendant switch with the feeder and overhead circuits including a pair of binding posts on the switch electrically connected with the switch mechanism and the means for directly connecting 100 the extension terminals with the feeder circuit including a third binding post on the switch electrically and independently connected with one of the terminal posts.

4. In electrical apparatus of the character 105 described, an attachment plug for one or more extension circuits comprising an insulating base, a pair of terminal blades projecting from one end of said base and provided with binding posts for the connection 110 of an extension circuit thereto, said insulating base having insulating sockets in the opposite end thereof and a cord outlet in the side thereof leading to the binding posts and terminal posts housed in the insulating 115 sockets and electrically connected with the projecting terminal blades at the other end of the plug to thereby enable engagement of the projecting blades of a second attachment plug therewith. 120

5. In electrical apparatus of the character 125 described, an attachment plug for one or more extension circuits comprising an insulating base having openings extending therethrough from end to end, a pair of projecting terminal blades at one end of said base, terminal posts extending from the base of said blades into the openings aforesaid to be contacted by projecting terminal blades of a second attachment plug inserted into 130

said openings from the opposite end of the base and binding posts for an extension circuit at the foot of the projecting blades aforesaid, the insulating base having a cord outlet in one side between the ends thereof leading to said binding posts.

6. In electrical apparatus of the character described, an attachment plug for one or more extension circuits comprising an insulating base, a pair of terminal blades projecting from one end of said base and provided with binding posts for the connection of an extension circuit thereto, said insulating base having insulating sockets in the opposite end thereof and a cord outlet in the side thereof leading to the binding posts and terminal posts housed in the insulating sockets and electrically connected with the projecting terminal blades at the other end of the plug to thereby enable engagement of the projecting blades of a second attachment plug therewith, said terminal posts being positioned on the base with the centers thereof disposed substantially at right angles to the centers of the terminal blades.
7. A pendant switch comprising an insulating switch base having a switch chamber therein, switch contacts mounted in said chamber, binding posts on the switch base and electrically connected with said switch

contacts, insulating sockets at the lower end of the switch base and open to the bottom of the base to receive the blades of an attachment plug, a circuit extension terminal post extending from one of the switch contacts 35 into one of the insulating sockets in the bottom of the base and a second current extension post extending outside the switch chamber down into another of the insulating sockets in the bottom of the base.

8. In apparatus of the character described, a pendant switch comprising a switch base, switch mechanism carried thereby, a pair of binding posts on the switch base for said switch mechanism, exposed insulating sockets at the bottom of the switch base, circuit extension terminal means extending from one of the switch contacts down into one of the insulating sockets at the bottom of the switch base, a 50 third binding post on the switch base electrically independent of the switch binding posts and other circuit extension terminal means extending from said third binding post down to the other insulating socket at 55 the bottom of the switch base.

In witness whereof, I hereunto set my hand this 15th day of December, 1919.

DAVID CONLAN, JR.
